UNITED STATES PATENT OFFICE.

CHARLES FREDERICK FLETCHER, OF FARMINGTON, WEST VIRGINIA.

WRENCH.

1,392,318.

Specification of Letters Patent.

Patented Oct. 4, 1921.

Application filed May 26, 1921. Serial No. 472,643.

To all whom it may concern:

Be it known that I, CHARLES F. FLETCHER, a citizen of the United States, residing at Farmington, in the county of Marion, State 5 of West Virginia, have invented a new and useful Wrench; and I do hereby declare the following to be a full, clear, and exact description of the invention, such as will enable others skilled in the art to which it 10 appertains to make and use the same.

The invention relates to wrenches of the pivoted jaw type and has for its object to provide a device of this character wherein stationary jaw carried by a handle member 15 is provided, said jaw having pivoted thereto a movable jaw carried by a disk which disk is provided with a radially disposed shoulder, with which shoulder the vertically disposed adjusting screw coöperates for moving and holding the pivoted jaw to various 20 positions in relation to the stationary jaw.

A further object is to provide the disk of the pivoted jaw with an arcuate recess, in which recess the coiled spring is disposed, 25 which coiled spring coöperates with the pivoted jaw and the body of the handle for normally forcing the pivoted jaw to open position.

A further object is to provide the adjusting screw with rectangular shaped heads 30 disposed within similarly shaped recesses and held therein by the spring. Also to provide a thumb engaging nut on the adjusting screw, which nut coöperates with the 35 shoulder of the disk of the pivoted jaw.

With the above and other objects in view the invention resides in the combination and arrangement of parts as hereinafter set forth, shown in the drawings, described and 40 claimed, it being understood that changes in the precise embodiment of the invention may be made within the scope of what is claimed without departing from the spirit of the invention.

45 In the drawings:—

Figure 1 is a side elevation of a wrench, parts being broken away to better show the structure.

Fig. 2 is a top plan view of the wrench. 50 Fig. 3 is a detail view looking into the jaws of the wrench showing the wire cutting recesses.

Referring to the drawings, the numeral 1 designates a handle member, the forward 55 end of which terminates in a stationary jaw 2. The handle member 1 is provided with a

chamber 3, in which chamber is disposed a disk 4 carried by a movable jaw 5 which is pivoted on the screw 6. The disk 4 rotates in the chamber 3, and is rotated by the 60 thumb engaging nut 7 which engages a radially disposed shoulder 8 carried by the disk 4 and forces the disk 4 around against the action of the coiled spring 9, which coiled spring has its end 10 disposed in an 65 arcuate recess in the bottom side of the disk 4 and its end 12 in engagement with a rectangular portion 13 of a vertically disposed feed screw 14 on which the thumb engaging nut 7 is threaded. The rectangular shaped 70 portion 13 of the feed screw 14 is disposed in a rectangular shaped recess 15 of the handle member and is held therein by said coiled spring 9. The upper end of the feed screw 14 is rectangular shaped and disposed 75 within a rectangular shaped member 16 and also held therein by the coiled spring 9. It will be seen that when the rectangular shaped portions of the feed screw 14 are disposed in the recesses 15 and 16 that the 80 spring 9 connecting with the arcuate side 17 of the disk 4 will hold the feed screw and thumb engaging nut 17 in place and against displacement. However it will be seen that when it is desired to disassemble the wrench 85 it will only be necessary to remove the single screw 6 and when said screw is removed all of the parts of the wrench may be easily removed.

The disk 4 is provided with an inclined 90 recess 18, which recess coöperates with the recess 19 for receiving a wire or the like and cutting said wire when the jaws are forced together, in any manner desired. The rear end of the handle 1 is provided 95 with nut receiving recesses 21 and 22 whereby standard sizes of nuts may be received. It is to be understood that the jaws 2 and 5 may receive therebetween anything that is round, such for instance as pipe or rod, however if so desired nuts may be held therebetween.

From the above it will be seen that a pipe and rod wrench is provided which is simple in construction and one wherein the parts 105 have been reduced to a minimum thereby allowing the wrench to be cheaply constructed.

The invention having been set forth what is claimed as new and useful is:—

1. In a wrench, the combination with a body having a stationary wrench jaw at one

end, of a movable jaw provided with a disk, said disk being pivotally mounted in a recess of the body, a vertically disposed screw disposed within the recesses and having its ends 5 provided with rectangular shaped portions disposed in vertically aligned rectangular shaped recesses, a thumb nut threaded on said vertically disposed screw, a radially disposed shoulder carried by the disk of the 10 movable jaw with which shoulder the thumb screw engages, a coiled spring disposed within the recess of the body, said coiled spring having one of its ends disposed in an arcuate recess in the disk, the other end of 15 said screw engaging the lower rectangular shaped portion of the vertically disposed feed screw, said feed screw being maintained in engagement with the rectangular shaped recesses by means of the coiled spring 20 and the disk.

2. In a wrench, the combination with a body having a stationary wrench jaw at one end, of a movable jaw provided with a disk, said disk being disposed in a recess of the body, a spring for normally holding said 25 jaws open, a lug carried by the disk, a feed screw detachably disposed in recesses in communication with the recess of the body, a thumb nut threaded on said screw and engaging the lug carried by the disk, said disk and said spring forming means for holding the feed screw against displacement.

In testimony whereof I have signed my name to this specification in the presence of two subscribing witnesses.

CHARLES FREDERICK FLETCHER.
